UNITED STATES PATENT OFFICE.

DELMAR G. HURD, OF LOWELL, MASSACHUSETTS, ASSIGNOR OF ONE-HALF
TO MICHAEL J. BURNS, OF SAME PLACE.

ADVERTISING APPARATUS.

SPECIFICATION forming part of Letters Patent No. 662,987, dated December 4, 1900.

Application filed March 6, 1900. Serial No. 7,460. (No model.)

To all whom it may concern:

Be it known that I, DELMAR G. HURD, a citizen of the United States, and a resident of Lowell, in the county of Middlesex and State of Massachusetts, have invented certain new and useful Improvements in Advertising Apparatus, of which the following is a specification.

My invention relates to advertising apparatus; and it consists in the devices and combinations hereinafter described and claimed.

In carrying out my invention I use a suitable case provided on opposite sides with windows or sight-openings through which the advertising-signs may be seen, and within this case I arrange to turn upon a horizontal axis a skeleton cylinder or lantern-wheel, on the bars or spindles of which are hung sign-plates or sign-boards bearing the desired advertisements. I provide suitable means for giving the lantern-wheel an intermittent motion to bring all the signs successively to the sight-openings. The motion of the cylinder or lantern-wheel is represented in the drawings as due to the progressive movement of a wagon, the body of which constitutes the case of the device, the shaft of the lantern-wheel being suitably connected by mechanism with the hub of one of the rear wheels; but any suitable motor having a wheel which revolves at a uniform speed might be used by connecting said last-named wheel to said cylinder or lantern-wheel just as the hub of said rear wagon-wheel is connected.

Some of the objects of this invention are to utilize both sides of the sign-plates or sign-boards, to guide them in such a manner that they shall be vertical at all times and shall not swing in order thereby to avoid noise and injury to said plates or boards and to display them properly at the windows or sight-openings of the case, to enable said plates or boards quickly and easily to be removed from the case and replaced therein, to allow other plates to be substituted for those previously in use, to move the signs to be exhibited quickly into place at the windows and to allow them to be displayed for a considerable period of time, and to provide automatic means for moving the signs.

In the accompanying drawings on two sheets, Figure 1 is a right-side elevation of

my invention set up in a closed wagon-body which serves as a case for the moving parts of the apparatus, said case or body and the rear axle being in section on the line 1 1 in Fig. 2, the front of the case or wagon-body and the front axle being omitted; Fig. 2, a rear view of the apparatus, showing also the case in vertical section on the line 2 2 in Fig. 6 1; Fig. 3, a vertical section of a part of the case through the sight-opening or window and of the bars or spindles of the lantern-wheel and the sign-plates or sign-boards; Fig. 4, an end elevation of a part of the guiding means, 65 the sign-boards being omitted; Fig. 5, a side elevation of one of said bars or spindles with its guiding-arms and adjacent parts of the lantern-wheel or cylinder, partly in central vertical section, at the left end; Figs. 6 and 7 70, respectively, a rear and a right side elevation of the wheels which cause the intermittent motion of the lantern-wheel or cylinder.

The cylinder A consists of two vertical heads $a a'$, connected by horizontal bars or spindles B, which are parallel with the shaft a^2 of said cylinder and pass through said heads near the peripheries of the same. The heads $a a'$ are fast on the shaft a^2 , so that the cylinder is in appearance like a lantern-wheel; but the spindles, instead of being fast in said heads, as in ordinary lantern-wheels, turn freely therein, so that as the cylinder and its horizontal shaft a^2 (which is supported in suitable stands $a^4 a^5$, secured on the floor a^3 85 of the case A) are revolved the bars B do not necessarily revolve about their own axles, but may have merely an orbital movement around said shaft.

Sign plates or boards C, adapted to bear 90 suitable written, printed, or painted advertising words or devices, are provided on their upper edges with suitable means by which said boards or plates may be attached to the bars B.

I prefer to suspend the plates below the bars B by the means shown in Fig. 3—that is, by clips D—each consisting of a pair of jaws d , and each jaw having on its upper end an incline d' , which descends toward the incline 100 of the other jaw of the same pair, and each jaw having below its incline d' a horizontal part or bottom d^2 , adapted to rest upon the top of a bar B. Each jaw d has a spring-shank

d^3 , which is secured to the face of the plate or board by any usual means, as by screws, opposite another similar jaw, two or more clips being used on each plate or board.

5 When the clip is pushed up against a bar B, the jaws open and reach up over said bar and close above the same, as shown.

If the bar B were round and fast in the heads $a a'$, the jaws would be worn rapidly 10 and would need to be lubricated to prevent noise, and the lubricating material would be likely to drip on the signs. Therefore the bars B are preferably loose in the heads $a a'$ and angular in cross-section or flattened on 15 one or more faces, and the jaws d bear upon a flattened side of said bar, so that the weight of the hanging signs tends to keep said bars from turning on their own axes and would probably be sufficient for that purpose if the 20 case A were stationary and the cylinder A were rotated by a stationary engine or similar motor. The bars B are represented as square in cross-section, their journals of course being cylindrical. Only the journals 25 of the bars B need to be lubricated in the construction shown, and these journals are not directly over the signs.

When the case A' is a wagon-body, Figs. 1 and 2, and is intended to be drawn over the 30 paving of streets and rough surfaces, it is necessary to use guides to keep the signs vertical, notwithstanding the jolting of the wagon. I therefore provide each bar B with two radial arms $b^1 b^2$, which extend in opposite directions from said bar, Fig. 5, outside of the 35 heads $a a'$ of the cylinder A, one or both of said arms being detachable from said bar to allow the latter to be passed through said cylinder-heads and each detachable arm being retained on said bar by any usual means, 40 as by a set-screw b^3 , which turns in the hub of said arm and thrusts against said bar. A stud b^4 is secured in the outer end of each arm $b^1 b^2$, as by a set-screw b^5 , in an obvious 45 manner, and preferably carries an antifriction-roll b^6 , which stud or roll bears against the inner surface of a stationary guide-ring E E', there being such a guide-ring at each 50 end of the cylinder A. (See Figs. 1, 2, 3, and 50.) The centers of both guide-rings lie in the same vertical plane with the axis of the cylinder A, but the center of one ring E is above and the center of the other ring E' below said axis an amount sufficient to keep 55 each stud b^4 (or the corresponding roll b^6 , if such be used) at all times against the inner surface of the corresponding guide-ring. The size of the guide-rings and the relative heights of their centers will depend, therefore, upon 60 the length of the arms $b^1 b^2$ and the size of the rolls b^6 .

It is obvious that the guiding means will hold any bar B the same side up throughout a complete revolution of the cylinder A and 65 that the clips D will prevent the sign from swinging on such bar and that therefore the sign will be vertical at all times. The inter-

mittency of the movement of the cylinder A is due, Figs. 1, 2, 6, and 7, to a toothed wheel F, having as many teeth f as there are boards 70 C, and to a cam-wheel G, which is almost a disk, except that its periphery is provided with a notch g and with a laterally-inclined cam portion g' , which at one end is continuous with the periphery of said wheel G and at 75 the other end is free or unattached at its outer curved surface and at its end is preferably flattened into parallelism with the lateral face of said wheel G to avoid scraping of said cam on the teeth f of the wheel F. These teeth f 80 next the opposite faces of the wheel F have each two working surfaces $f' f^2$ parallel to each other and in the plane of the axis of said wheel, the other two working surfaces $f^3 f^4$ of the same tooth adjacent to the opposite faces of said wheel being parallel to each other, but at the same angle with said axis as the cam portion g' has to the plane of the cam-wheel G. The wheels F G are set at right angles to each other, with the periphery 90 of the wheel G in one of the interdental spaces of the wheel F. The cam portion g' is offset from the wheel G a distance equal to the pitch of the teeth on the wheel F. It is evident that a complete revolution of the wheel G 95 will revolve the wheel F an angular distance measured by one tooth of said wheel F and that the movement of said last-named wheel will occupy but a small fraction of the time required for a complete revolution of the cam-wheel. Obviously the wheel F might be fast on the central shaft a^2 of the cylinder A and the wheel G fast on the shaft of any suitable motor.

For convenience a separate shaft f^5 , on which 105 the wheel F is fast, is connected to rotate the shaft a^2 of the cylinder, as by sprocket-wheels $f^6 a^6$, fast on said shafts, respectively, and connected by a sprocket-chain f^7 in a well-known manner.

The wheel G is represented as fast on a shaft g^2 , which is driven by a sprocket-chain g^3 , which connects sprocket-wheels, one, g^4 , of which is fast on said shaft g^2 and the other, h , of which is fast on the hub h' of a rear driving-wheel H of the wagon.

Motion of the cylinder is caused by the turning of the wheel H as the wagon is drawn forward; but obviously the wheel h might be rotated with the same effect by any motor.

If springs I are used, as represented in Figs. 1 and 2, between the rear axle and the case or wagon-body A', some means must be provided to keep the chain g^3 taut when the case moves toward the rear axle. I use for this purpose two idle pulleys $j j'$, arranged to press the members of said chain toward each other, said pulleys being carried by the lower ends of swinging arms J J, pivoted to the under side of the case and drawn toward each other 120 by the contraction of a spiral spring j' , the ends of said spring being secured to said arms J J, respectively.

Access to the case for repairs or to change

the signs is obtained through any suitable door (represented as a trap-door a^7) hinged at a^8 in the floor of the case and opening upward.

5 I claim as my invention—

1. In an advertising apparatus, the combination with a suitable case, having sight-openings at opposite sides thereof, and a cylinder arranged between said sight-openings and 10 consisting of a central horizontal shaft, and heads, fast on said shaft, of sign-plates, suspended between said heads, parallel with said shaft each sign-plate being free to swing between said heads and between the next adjacent sign-plates and adapted to maintain a 15 vertical position at all times and to present its opposite faces at said opposite sight-openings in close proximity thereto as said cylinder is revolved.
2. In an advertising apparatus, the combination with a suitable case, having sight-openings at opposite sides thereof, and a cylinder arranged between said sight-openings and consisting of a central horizontal shaft, 20 heads, fast on said shaft, and bars connecting said heads, parallel with said shaft, of sign-plates, suspended from said bars, each sign-plate being free to swing between said heads and between the bars of the next adjacent sign-plates and adapted to maintain a 25 vertical position at all times and to present its opposite faces at said opposite sight-openings in close proximity thereto as said cylinder is revolved.
3. The combination with a cylinder 30 consisting of heads, a central, horizontal shaft on which said heads are fast, and bars, arranged parallel with said shaft and journaled in said heads and free to turn therein, of plates and 35 clips rigidly secured to said plates and adapted to engage said bars, said bars having one

or more flat faces and said clips having corresponding inner faces to prevent said plates from turning on said bars.

4. The combination, in an advertising apparatus, of a case, having opposite sight-openings, a cylinder, consisting of heads, a shaft, on which said heads are fast, and bars, journaled in said heads, parallel with said shaft, and having at opposite ends oppositely-projecting radial arms, provided with studs, plates, rigidly secured to the said bars, and guiding means adapted to keep every position of each plate parallel with every other position of the same when said cylinder is 55 rotated, said shaft being arranged horizontally between said sight-openings.

5. The combination in an advertising apparatus, of a case, having opposite sight-openings, a cylinder consisting of heads, a 60 central horizontal shaft, on which said heads are fast, said shaft being arranged between said sight-openings, and bars, journaled in said heads parallel with said shaft and having at opposite ends oppositely-projecting radial arms, provided with studs, arranged parallel with said bars, plates, rigidly secured to said bars, and stationary guide-rings, arranged at opposite ends of said cylinder and having their corresponding curved surfaces 70 in contact with said studs, said rings being eccentric to said cylinder but having their centers in the same plane with the center of said cylinder, to keep every position of each plate parallel with every other position of 75 the same when said cylinder is rotated.

In testimony whereof I have affixed my signature in presence of two witnesses.

DELMAR G. HURD.
